UNITED STATES PATENT OFFICE.

JOHN L. PERKINS AND JOHN O. STANLEY, OF HOLYOKE, MASSACHUSETTS.

MACHINE FOR REDUCING RAGS OR PAPER.

No. 864,552.

Specification of Letters Patent.

Patented Aug. 27, 1907.

Application filed December 14, 1906. Serial No. 347,834.

To all whom it may concern:

Be it known that we, JOHN L. PERKINS and JOHN O. STANLEY, citizens of the United States of America, and residents of Holyoke, in the county of Hampden and State of Massachusetts, have invented certain new and useful Improvements in Machines for Reducing Rags or Paper, of which the following is a full, clear, and exact description.

This invention relates to a machine for cutting or reducing rags for paper stock, paper or other material, into suitably small, and more or less nearly similarly shaped and uniformly sized pieces.

An object of the invention is to devise a machine for the purpose indicated which has the capability of a large amount of stock reduction in a given time.

Another object is to so construct the machine that it may have a long life, notwithstanding the wear to which the parts, especially the shears comprised therein, are subjected. Another object of the invention is to so construct the machine that the shear comprising parts therein become self sharpening. And another object of the invention is to so construct the machine that it is of unusual simplicity, of cheapness of manufacture, and great durability.

25 The invention is described in conjunction with the accompanying drawings and the particular features thereof are covered in the claims.

In the accompanying drawings,—Figure 1 is a plan view of the machine; Fig. 2 is a sectional elevation as taken on line 2—2, Fig. 1; Fig. 3 is a perspective view, with parts broken away, of the portion of the machine which is herein termed the "fixed bed plate". Fig. 4 is a perspective representation of some of the individual teeth and spacing blocks comprised in the bed 35 plate; Fig. 5 is a perspective view illustrating a bed plate of modified form.

Similar characters of reference indicate corresponding parts in all of the views.

In the drawings,—A represents the frame of the machine comprising opposite upright sides 10, 10, having L-shaped lugs 12, 12, on the inner faces thereof, each provided with an aperture 13.

B represents a rotatable body or cylinder journaled in said frame and having essentially one, and in practice 45 preferably a plurality of helically extending series of outwardly projecting separated tapered teeth 14, 14. The shaft or arbor of the rotatable body B has a large spur gear wheel 15 thereon, meshing into which is a considerably smaller spur gear wheel 16 affixed on the 50 driving shaft 17 to which the driving pulley 78 is provided whereby the rotation of the shaft through means of a belt may be accomplished for the driving of the rotatable tooth carrying body at appropriate speed and with great power.

55 C represents the portion of the machine, which, as an entirety, is herein termed the "bed plate", the

same having a series of separated teeth evenly spaced and arranged in a horizontal line parallel with the axis of the cylinder B and positioned so that the teeth revolvably carried by the cylinder will successively pass with shearing actions in close contact with the surfaces of, and through the spaces between, the teeth of the bed plate, which latter teeth are tapered so that both sets of teeth and the walls of the intermediate spaces between the individual teeth are complementary to each other.

Describing the bed plate exactly as constructed and mounted in the preferred form, it will be perceived that the same comprises an L-shaped bar a having appurtenant thereto and located above the ledge portion 18 thereof, a section 19 in the form of a rigid metallic strap, arranged vertically adjustable relatively to the part 18 by the screws 20 which have thread engagements vertically through such portion 18 with upper end supporting bearings against the underside of the section 19. The L-shaped bar is supported at its end portions on the aforementioned opposite L-shaped lugs 12 of the frame sides. The series of teeth b of the bed plate are constituted by tooth sections in the form of comparatively vertically long, or high, steel blocks, the bases of which rest on the vertically adjustable section 19. The upper ends of the said tooth sections or blocks extend considerably above the upper edge of the L-shaped bar a, all terminating at a normal level more or less nearly corresponding to that of the axis line of the cylinder B. The blocks are at their upper end portions forwardly tapered, as indicated at 22, conformable to the tapering or beveling of the teeth projecting outwardly from the cylinder.

23 represents spacing blocks between the tooth sections, the same being of the same height as such tooth sections, but of considerably less width so as to leave the proper tooth spacing and to constitute, by their upper forward portions, shear edges 24, against which 85 the points of the cylinder teeth coact, while the sides of the cylinder teeth coact with the lateral edges or upper corners of the said tooth sections. The upper bed plate surface, constituted by the upper ends of the closely united tooth sections and spacing blocks, 90 is one that is horizontal and flush. The blocks 25, shorter than the tooth sections and spacing blocks, are provided between the lower portions of the tooth sections and are positioned facewise against the spacing blocks.

105 d represents a clamping plate of the same length as the L-shaped bar or body a of the bed plate. This clamping plate is firmly secured on the forward edge of the horizontally disposed ledge member 18 of the aforesaid bar a, being secured by the screws 27, and 110 tightly binds all of the tooth sections and spacing blocks, so that when united the tooth comprising

plate is to all intents and purposes the same as if integrally made.

The bed plate bar *a* has end cheeks or right angular vertical lugs 28, 28, to constitute stops against which 5 may be positioned the tooth sections and intermediate blocks, and also against which engage the inner ends of screws 30 which have thread engagements horizontally through the frame sides in a line of the length of the bar *a*. These screws 30 are available for positioning 10 and holding the tooth comprising bed plate positioned with exactness, so that the centers of the spaces between the bed plate teeth will be coincident with the centers of the teeth of the cylinder.

32, 32, represent adjusting screws passing through 15 the lugs 12 at the inner portions of the frame sides in lines at right angles to the length of the bed plate bar *a* and with bearings against the back thereof; and 33, 33, represent a pair of screws extending horizontally loosely through the apertures 13 therefor in the afore- 20 said opposite side lugs 12, and with screw thread engagements into the opposite end portions of the bar *a*. By loosening the screws 33 and turning up the screws 32 the bed plate may be bodily set forwardly in slight extents, towards the axis of the cylinder, as may be 25 required from time to time in consequence of the wearing away of the shearing parts, more especially the teeth of the cylinder. And after the bed plate shall have been slightly forwardly moved, the confining screws 33 are again tightened so that their heads bind 30 against the rear side of the lugs 12 outside of the margins of the slot 13. The slots 13 are made slightly wider than the diameter of the shanks of the screws 33 so that there may be a slight play of the screws horizontally in an endwise adjustment of the bed plate, see Fig. 1.

35 *ff* represent a pair of feed rolls to the rear of the bed plate teeth with their nipping part adjacent peripheral portions at or slightly above the level of the tops of the bed plate teeth; and *g* represents a chute or guide for the rags or other stock to be brought to reducing action 40 by the machine. The said feed rolls are geared together at one end of each, 37 representing the intermeshing spur gears therefor; and the lower feed roll has on the opposite end from that on which is secured one of the gears 37 a larger spur gear wheel 38 which 45 meshes with a spur gear wheel 39 which is fast on the arbor, or integrally formed journal, of the cylinder *B*,—this last mentioned gearing constituting the driving means for the feed rolls.

The stock fed to and through the feed rolls and advanced forwardly therebeyond over the teeth of the bed plate is cut into four sided small pieces, the shapes thereof corresponding to those of the complementary teeth of the bed plate cylinder; and because of the helical arrangement of each of the endwise arranged 55 rows or series of the cylinder teeth, a cylinder tooth at one end reaches the shearing plane and performs its individual cutting action slightly before the next revolving cylinder tooth of the same series, so that there is a distribution, as to time, within the period 60 of passage of a helical series of cylinder teeth past the bed plate teeth, of the shearings performed by and between individual pairs of the teeth.

The teeth of one of the tooth comprising bodies in this machine, preferably those of the cylinder, are 65 composed of a softer metal than are the teeth of the

relatively opposed body; and in practice the bed plate teeth are composed of steel, hardened; and the cylinder with its outwardly extending teeth arranged in gradually sweeping helical lines is made of cast iron. Consequently the cylinder teeth are self sharpening 70 in their shearing passages through and in relation to the harder bed plate teeth. From time to time as the cylinder teeth are perceived to have been worn away, the bed plate is very slightly forwardly adjusted,—the provisions for which have been hereinabove pointed 75 out,—so that the complementary sets of teeth will bottom and be in shearing contact at all of the tooth sides and intermediate walls.

The cylinder teeth are constructed with reinforcing rear ribs or webs 45 whereby liability of tooth break- 80 age is lessened.

The bed plate may be bodily taken out from the machine and the plane top surface thereof ground from time to time as the bed plate top may be found to be worn and dull at the corners or shear edges of and between the bed plate teeth; and to compensate for any reduction in the height of the teeth, the tooth series may be bodily slightly elevated by the adjusting screws 85 20 operable to slightly raise the movable bed plate section 19 on which the series of individual tooth sections and their spacing blocks rest.

As hereinabove intimated, the bed plate is to all intents and purposes an entirety, or the same as if integrally made, so far as its function is concerned, for a given period of effective operativeness; but by making 95 it sectional as regards the individual tooth sections, the latter are susceptible of being made of very simple and easily produced forms from good steel and satisfactorily hardened, and wear compensation provided for.

In Fig. 5 a bed plate is represented in which the tooth sections *b*² are horizontally arranged and clamped within an L-shaped bar *a*², the longer diameter of which latter is also horizontal,—the object of this illustration being to indicate that the precise formation and arrangement of a bed plate such as represented in the preceding views need not necessarily be strictly followed, although such is the preferred one for reasons of practicability and expediency.

It will be seen that, in both the form of bed plate 105 illustrated in Fig. 5 and that shown in the remaining views, the fixed tooth members are mounted in what is, in effect, a casing, composed of the L-shaped bar with its end members, and the clamping plate. In both forms, also, means is provided for adjusting the tooth members, and the spacing members, in and out of the open side of the casing.

A machine made in accordance with this invention is especially available for the reduction of rags for paper stock; and such machine has also been extensively utilized in the manufacture of confetti from tissue paper.

We claim:—

1. In a machine of the character described, the combination of a fixed body comprising a series of spaced teeth, a rotatable body carrying teeth complementary to said other teeth and arranged to pass therebetween with a shear action, and means for securing relative adjustment of said bodies in a direction tangential to said rotatable body.

2. In a machine of the character described, in combina-

- tion, a fixed series of separated teeth, and a rotatable body having a series of teeth complementary to those of the fixed series and adapted to pass with a shear action therebetween, and means for adjusting the fixed series tangentially of the rotatable body.
5. In a machine of the character described, in combination, a fixed series of separated teeth, and a rotatable body having a series of teeth complementary to those of the fixed series and adapted to pass with a shear action therebetween, means for adjusting the series of fixed teeth in a direction towards the rotatable body, means for adjusting said series parallel to the axis of the rotatable body, and means for adjusting the series tangentially of said rotatable body.
10. 4. In a machine of the character described, the combination of a holder casing, a series of spaced independent tooth members projecting therefrom, and means for clamping said series rigidly within the casing, and of a rotatable body having projecting spaced teeth arranged to pass with a shearing action between said other teeth.
5. In a machine of the character described, the combination of a fixed holder casing, a series of spaced independent tooth members projecting therefrom, spacing members alternating with said tooth members, and means for clamping said series endwise rigidly within the casing, and of a rotatable body having projecting spaced teeth arranged to pass with a shearing action between said tooth members.
25. 6. In a machine of the character described, the combination of a holder casing having one side removable, a series of spaced independent teeth projecting from said casing and clamped therein by said removable side, and a rotatable body having a series of spaced projecting teeth arranged to pass with a shearing action between said other teeth.
30. 7. In a machine of the character described, the combination of a holder casing, a series of spaced tooth members projecting therefrom, and means for adjusting said series within the casing, and of a rotatable body having a series of spaced projecting teeth arranged to pass with a shearing action between said tooth members.
40. 8. In a machine of the character described, the combination of a holder casing having one side open, a series of spaced independent teeth projecting from said casing, and means for adjusting said series simultaneously in the direction of their length in and out of such open side, and of a rotatable body having a series of spaced projecting teeth arranged to pass with a shearing action between said other teeth.
45. 9. In a machine of the character described, the combination of a holder casing, a series of spaced independent teeth projecting from said casing, means for adjusting said series simultaneously in and out of said casing, and means for adjusting said casing at right angles to the last mentioned adjustment, and of a rotatable body having a series of spaced projecting teeth arranged to pass with a shearing action between the teeth within the casing.
50. 10. In a machine of the character described, the combination of a holder casing, means for adjusting said casing in two directions at right angles to each other, a series of spaced independent tooth members projecting from said casing, and means for adjusting said series simultaneously in and out of the casing at right angles to said other adjustments, and of a rotatable body having a series of spaced projecting teeth arranged to pass with a shearing action between the tooth members.
55. 11. In a machine of the character described, the combination with a fixed bed-plate comprising a series of separated forwardly tapered teeth, of a rotatable cylindrical body having a series of correspondingly tapered teeth arranged along the length of, and extended outwardly from the side of such cylinder and operable as an interdental shears in conjunction with the bed plate teeth, means for rotating the cylinder and means for securing an adjustment of one of the tooth series in a direction towards the other.
60. 12. In a machine of the character described, the combination with a fixed bed-plate comprising a series of separated teeth, of a rotatable cylindrical body having series of teeth arranged in helical lines along the length of and extended outwardly from the side of such cylinder, each of said teeth having a reinforcing rib at its rear side of less thickness than the tooth, and means for rotating the cylinder.
65. 13. In a machine of the character described, the combination with a supporting frame, a cylinder horizontally mounted therein, having a series of separated outwardly projecting teeth, and means for rotating the cylinder, of an L-shaped bar supported horizontally by the frame parallel with the cylinder, a series of separated tooth members, mounted on said bar, and a clamping plate secured to the bar and binding the tooth members against the back thereof. 85
70. 14. In a machine of the character described, the combination with a supporting frame, a cylinder horizontally mounted therein, having a series of separated outwardly projecting teeth, and means for rotating the cylinder, of an L-shaped bar supported horizontally by the frame parallel with the cylinder, a series of separated tooth members, mounted on said bar, a clamping plate secured to the bar and binding the tooth members against the back thereof, and means appurtenant to said L-shaped bar and 100 operable to adjust said tooth members vertically. 95
75. 15. In a machine of the character described, the combination with a supporting frame, a cylinder horizontally mounted therein, having a series of separated outwardly projecting teeth, and means for rotating the cylinder, of an L-shaped bar supported horizontally by the frame parallel with the cylinder, a series of separated tooth members, mounted on said bar, a clamping plate secured to the bar and binding the tooth members against the back thereof, and means for adjusting said L-shaped bar forwardly towards the axis of the cylinder. 105
80. 16. In a machine of the character described, the combination with a supporting frame, a cylinder horizontally journaled therein, having a series of separated outwardly projecting teeth, and means for rotating the cylinder, of an L-shaped bar supported horizontally by the frame parallel with the cylinder, a vertically adjustable section appurtenant to said bar and above the ledge portion thereof, a series of individual separated tooth members resting on said adjustable section and blocks between and 110 115 of less width than said tooth members, having their upper ends flush with the tops of such members and a clamping plate secured on the front of the L-shaped bar having a clamping engagement against the forward faces of said teeth members. 120
85. 17. In a machine of the character described, the combination with a frame comprising opposite upright sides having L-shaped lugs, on the inner faces thereof, provided with apertures and a rotatable body journaled in said frame having a series of outwardly projecting separated teeth, and means for rotating said body, of an L-shaped bar extending between and supported by said lugs, a vertically adjustable section above the ledge portion thereof, screws passing through said ledge portion and having adjusting engagements with said section, a series of individual tooth members resting on said adjustable section, and bearing against the back of the L-shaped bar, a clamping plate and means for confining it on the L-shaped bar against the forward faces of the tooth members, spacing blocks between the tooth members, headed screws having the shanks thereof extended loosely through the apertures in said L-shaped lugs and screw engaged into the L-shaped bar, and screws threading through the L-shaped lugs and against the back of the L-shaped bar. 130
90. 18. In a machine of the character described, the combination with a fixed bed plate comprising a series of spaced teeth and a pair of feed rolls thereabove, geared together at one end, and one thereof having an additional gear wheel at its other end, of a rotatable body having a series of outwardly extended teeth operable as interdental shears in conjunction with the bed plate teeth, a driving shaft having a small spur gear wheel thereon, a larger spur gear wheel connected with the rotatable body in mesh with the driving shaft gear, and another spur gear wheel connected with said rotatable body and in driving connection with the gear wheel on one end of one of said feed rolls. 140
95. 19. In a machine of the character described, the combination of a fixed casing or holder, a movable strip therein, a series of spaced independent tooth members projecting at 160 145 150 155 .

one end without the casing and bearing at their other ends against said strip, means for adjusting said strip to carry said tooth members endwise, and a rotatable body having a series of spaced projecting teeth arranged to pass with a shearing action between said tooth members.

20. In a machine of the character described, the combination of a fixed casing or holder, a series of independent tooth members projecting therefrom, spacing members of less depth than said tooth members and alternating there-

10 with and having their projecting ends flush with the projecting ends thereof, and means for clamping said several members within the casing, and of a rotatable member having a series of spaced projecting teeth arranged to pass with a shearing action between said tooth members.

15. 21. In a machine of the character described, the combination of a fixed casing or holder, a series of independent tooth members projecting therefrom, spacing members of

less depth than said tooth members and alternating there-with and also projecting without the casing, short blocks contiguous the faces of said spacing members adjacent 20 their inner ends and completing the filling of the inter-dental spaces at these regions, and means for clamping said several members and blocks together within the casing, and of a rotatable body having a series of spaced projecting teeth arranged to pass with a shearing action 25 between the tooth members and along the faces of said spacing members.
